MIXING DEVICE FOR WATER LINES

Paul F. Otto and Edward H. Warne,
Menlo Park, Calif.

Application July 10, 1947, Serial No. 759,960

3 Claims. (Cl. 299—84)

1

This invention relates to a regulated visual mixing device for water lines and the like.

The primary object of the invention is to provide a visual device to introduce bath salts in crystal, cartridge, or other form, or water softener, soap, medicated or chemical substances into water lines, such as the conduits leading to a shower bath or the like.

The main feature of the invention is the bypassing of a regulated amount of water through a control or regulating valve into a visual dissolving or mixing chamber, which latter can be easily refilled, in cartridge or other form, with the soluble chemical substance to be introduced in the water, such as bath salts, water softener, soap and the like, and which easily determines the regulated degree of mixture that shall be introduced into the water as it issues from an outlet, such as a shower nozzle.

We are aware that some changes may be made in the general arrangements and combinations of the several devices and parts, as well as in the details of the construction thereof without departing from the scope of the present invention as set forth in the following specification, and as defined in the following claims; hence we do not limit our invention to the exact arrangements and combinations of the said device and parts as described in the said specification, nor do we confine ourselves to the exact details of the construction of the said parts as illustrated in the accompanying drawings.

With the foregoing and other objects in view, which will be made manifest in the following detailed description, reference is had to the accompanying drawings for the illustrative embodiment of the invention, wherein:

Fig. 1 is an assembly view showing the device installed in a shower line.

Fig. 2 is a sectional view of our insert unit in said shower line.

In Fig. 1 is shown somewhat diagrammatically a water line 1 which is suitably supported in a wall 2. At the top of the line 1 is the usual outlet conduit 3 on the end of which is mounted a shower nozzle 4 of any suitable type. At the regular height and regular position on the line 1 is provided a valve mechanism 6, the handles 7 of which are manipulated from the front and outside of the wall 2 in the usual manner to regulate the amount and temperature of the water flow to the shower. It is customary that two lines 8 are leading up to the mixing valve mechanism 6 and there are two handles 1, one for hot water and the other for cold water, so that the

2

person using the shower can adjust and mix the hot and cold water to the desired temperature of the shower.

The single line 1 which extends from the valve mechanism 6 to the shower is interrupted in the wall and there is interconnected between the parts of the water line 1 our mixing device denoted in its entirety by the numeral 9.

This mixing device 9 is made as a unit so as to form an appliance, fixture or attachment whereby a regulated strength of a soluble substance is dissolved and introduced into the water line. The unit includes a section 11 adapted at its intake end 12 and outlet end 13 to be screwed into the water line 1 either directly or by suitable union connections. This section 11, in this illustration, is concealed within the wall together with the line 1. An intake arm 14 extends from the section 11 near the intake end 12 and to the outside of the wall 2. An outlet arm 16 extends from the section 11 near the outlet end 13 thereof to the same side as the intake arm 14.

In the intake arm 14 is an intake passage 17. An outlet passage 18 is formed in the outlet arm 16. The passages 17 and 18 are inclined at a suitable angle from the section 11 converging outwardly.

A mixing chamber 19 is formed between the outer ends of the arms 14 and 16 and the passages 17 and 18 therein. A cup 21 on the outer end of the intake arm 14 is the bottom of the mixing chamber. The cup 21 has a substantially frusto-conical recess 22 therein, into a side of which extends the intake passage 17. A shoulder 23 in the cup 21 determines a socket 24 which latter accommodates an end of a transparent chamber tube 26, a packing gasket, such as a ring gasket 27 is between the end of the chamber tube 26 and the shoulder 23 and seals the socket 24.

The top of the mixing chamber 19 is formed by an internally threaded tubular bracket 28 on the outer end of the outlet arm 16, into a side of which bracket 28 connects the outer end of the outlet passage 18. A socket 29 in the inner end of the tubular bracket 28 holds the upper end of the transparent chamber tube 26.

A packing gasket, such as a ring gasket 31 is on the upper end of the chamber tube 26. A locking ring 32 threaded in the bracket 28 engages the ring gasket 31 and holds the chamber tube 26 in place.

A plug 33 seals the top of the bracket 28. A suitable gasket 34 between the top edge of the bracket 28 and the head of the plug 33 renders the cover watertight. In the inside wall of the

plug 33 is threaded a screw 36 on the head 31 of which is supported a screen 38 by a nut 39, to prevent the passage of solid particles from the chamber into the outlet passage 18. This screen structure is adjustable by the screw 36 to selected spacing from the plug 33 to suit various heights of chamber tubes. The locking ring 32 renders the length of the upper socket 29 and of the mixing chamber variable to suit various types of chamber tubes or cartridges.

The inner end 41 of the intake passage 17 is turned into the intake end of the section 11 and is separated from the main passage of the section 11 by a partition baffle 42. In other words the section 11 is divided at the intake end 12 into a substantially parallel main line passage for clear water and an intake by-pass 41.

A regulator valve stem 43 is journaled in the intake arm 14, below the intake passage 17. The inner end of the valve stem 14 is a double passage valve simultaneously controlling the main line passage and the intake by-pass 41. In the herein illustration this is accomplished by valve passages 44 and 46 respectively across the by-pass 41 and the main line of the section 11. These valve passages 44 and 46 are transverse on the valve stem 43 and are offset at right angles to one another, so that one valve passage is fully open when the other is fully closed. A number of selected relative valve adjustments can be accomplished by turning the valve stem 43. A suitable handle 47 is provided for the regulator valve. A suitable packing 48 seals the outer end of the valve stem 43 in the arm 14.

The unit herein described is attached in the line 1 in the manner heretofore stated, and usually beyond the regular water temperature regulating valve device 6, so that the outlet nozzle temperature is not affected when the unit is in operation or when the unit is turned off. This unit may be inserted in various types of lines with various types of coupling devices. It may be installed if necessary so that the intake end 12 is at the top and the outlet end 13 is on the bottom so that the flow is downward, according to the requirement of the particular application. The transparent chamber tube 26 may be made of either plastic or glass or the like, and it may assume any desirable shape, cylindrical or otherwise. This chamber tube may be a tube more or less permanent and refillable by removing the plug structure and then replacing the bath salts or other substance therein, or the entire tube may be used as a replaceable cartridge.

In operation, desired temperature of water is obtained in the usual manner through the main valve device 6. Then the mixture regulating control valve handle 47 is turned from the position shown in Fig. 2 to a position where the main passage in the section 11 is partly restricted and the by-pass passage 41 is partly opened by the respective adjustment of the valve passages 46 and 44. The user can readily observe the water by-passing through the transparent chamber tube 26 and the solution is correspondingly regulated.

In our device a regulated ratio of flow through the mixing chamber and through the main line is readily achieved by the mere turning of a mixture control valve. The forming of the solution in the mixture chamber is under visual control. The quantity of the soluble substance in said visual mixture chamber is always observable. The mixture chamber can be refilled without danger of water flow and without interfering with the water line, even while the main water

line is open. The device can be regulated during its operation, from complete shut off adjustment, by-passing no water at all, and allowing flow of clear water from the outlet, to a complete by-pass of the total water flow through the mixing chamber for a stronger solution at the outlet; and to all intermediate ratios between said extreme adjustments. The mixing with solvent is thorough. The unit can be easily attached to and installed in existing water lines, and is eminently adapted for its purposes.

We claim:

1. A mixing unit for water lines, comprising a body section formed into a conduit and adapted to be interconnected in the water line, an arm extended from about each end of the conduit and away from said water line, a socket on the outer end of each arm, said sockets being spaced from one another and from said water line, a transparent container held in said sockets and being adapted to contain a soluble substance and to permit water flow therethrough, an intake passage extended through one of said arms from said body section conduit to the adjacent socket, a return passage extended from the socket of and through the other arm to said body section conduit, a valve device on said first arm for selectively and simultaneously regulating the flow through said body section conduit and into said intake passage, and a valve adjusting element extended through said first arm to the outside of and adjacent said mixing chamber for manipulating said valve device.

2. A mixing unit for water lines, comprising a body section formed into a conduit and adapted to be interconnected in the water line, an arm extended from about each end of the conduit and away from said water line, a socket on the outer end of each arm, said sockets being spaced from one another and from said water line, a transparent container held in said sockets and being adapted to contain a soluble substance and to permit water flow therethrough, an intake passage extended through one of said arms from said body section conduit to the adjacent socket, a return passage extended from the socket of and through the other arm to said body section conduit, a valve device on said first arm for selectively and simultaneously regulating the flow through said body section conduit and into said intake passage, said first arm having a recess therein at the socket thereof into which said intake passage discharges, the other socket being open to allow access to said container, a removable closure for said open socket, and a valve stem extended from said valve device away from said body section and through said first arm for manipulating said valve device.

3. A mixing unit for water lines for shower baths and the like, comprising a body section formed into a conduit and adapted to be interconnected in the water line, an arm extended from about each end of the conduit and away from said water line, a socket on the outer end of each arm spaced from said conduit, said sockets being spaced from one another, a transparent container held in said sockets and being adapted to contain a soluble substance and to permit water flow therethrough, an intake passage extended through one of said arms from said body section conduit to the adjacent socket, a return passage extended from the socket of and through the other arm to said body section conduit, an element to divide the body section conduit at said intake passage into an intake leading into said

intake passage and a port leading into said body section conduit, a regulating valve extended through said intake and said port and having valve passages offset relatively to one another for simultaneously and inversely regulating the opening through said intake and through said port, and valve control means extended through the arm at the intake passage away from said body section and to the outside for manipulating said regulating valve.
